(57) **CLAIM**

I claim the ornamental design for a headboard, as shown and
described.

DESCRIPTION

Cross-reference is made to U.S. Design patent application
Ser. No. 29/566,378 entitled "Headboard for a Patient Bed"
which is filed on the same day as the present application and
is expressly incorporated herein by reference.

FIG. 1 is a front perspective view of the design of the
headboard;

FIG. 2 is a front elevation view of the design of FIG. 1;
FIG. 3 is a rear elevation view of the design of FIG. 1;
FIG. 4 is a top plan view of the design of FIG. 1;
FIG. 5 is a bottom plan view of the design of FIG. 1;
FIG. 6 is a first side elevation view of the design of FIG. 1,
with the opposite, second side elevation view being a mirror
image of the first side elevation view; and,
FIG. 7 is a rear perspective view of the design of FIG. 1.
The features shown in broken lines depict environmental
subject matter only and form no part of the claimed design.
